BERET

Anita Andra, New York, N. Y.

Application March 15, 1943, Serial No. 479,193

1 Claim. (Cl. 2—198)

1

The present invention relates to headwear, and particularly to that type known as a beret. A principal object of the invention is to provide a simple and attractive cap of the beret type which can be worn as an article of dress for street wear.

A further object is to provide a new cap adapted to be worn by women employed in machine shops and other places where it is important for them to keep dust and grease out of their hair as well as to keep their hair confined to avoid getting it caught in machinery.

Within the last year or two, a number of safety caps have been offered to, and some adopted by various plants throughout the country, for use by their female workers, but these have been deficient or unsatisfactory in one respect or another, and, always at best, where adopted, have constituted a compromise. Certain of these devices constituted snoods which, while confining the hair, failed to keep out dust, oil and grease. Others took the form of tailored caps which fitted snugly against the skull, confined the hair and kept out dust, oil and grease, but were uncomfortable because of tight fit, and, being tailored to fixed curved form, could not be conveniently ironed though no difficulty may have been experienced in laundering the same. Others were compromises between the snood and the boudoir or dust type of cap, with and without visor.

It is one of the principal virtues of my invention that the beret is made out of a flat piece of fabric which is adapted to be readily folded to form the article as it is to be worn, and to be as readily unfolded so that it may be conveniently laundered, dry cleaned, ironed and stacked compactly.

Where the female employees are likely to come in contact with grease or oil, the fabric employed may be oil- or grease-proofed. Oiled rayon may be used for this purpose, and it can be designed to have as attractive an appearance as, say, a printed cotton fabric with an attractive design.

The flat form is so designed that when folded in the manner indicated later, the resulting beret will comfortably fit the head around the "band" region, yet will have sufficient space to accommodate large masses of hair without constriction.

Heretofore, berets have been made with an elastic band sewn into the beret proper and consequently, while it was amenable to dry cleaning or washing, it could not, because of its peculiar form, be ironed with the degree of convenience and perfection with which it was desired.

It is an important feature of the present invention that the beret may, by virtue of the

means hereinafter to be described, be flattened out in a single plane, so that washing or dry cleaning and ironing can be expedited, and thus the life and use of the article greatly increased.

5 By my peculiar construction also, the beret is endowed with a series of peaks radiating from the crown, producing a flare and giving to the beret a pleasing and attractive appearance.

It will thus be seen that I have provided an 10 article consisting of a flat piece of fabric which is designed to be convertible into a beret type of cap which can be used for dress wear or as a safety cap in industry, which said piece is preferably adapted to be folded in triangular folds 15 around the periphery thereof and thereby to effect a polygonal form in the crown. The latter mode effecting the desired results is, of course, one practical mode of application, the scope of 20 the invention being measured by the appended claim.

Referring to the accompanying drawings exemplifying a preferred embodiment of my invention,

Fig. 1 shows a flat blank of material from 25 which the beret is formed.

Fig. 2 is a bottom view of the beret after the several portions of the blank of material have been folded over and united.

Fig. 3 is a fragmentary sectional view taken on the line 3—3 of Fig. 2, showing clearly the nature 30 of the fold.

Fig. 4 is a side view of the beret showing more clearly the series of "peaks" radiating from the crown.

Fig. 5 is a front view of the beret as it looks 35 upon the person.

Fig. 6 is a fragmentary view of the piece of material from which the beret is formed, showing a modified form employing snap fasteners instead of the button and buttonhole means of 40 securing the folds together.

Fig. 7 is a fragmentary cross-section showing the manner of securing the folds of the blank shown in Fig. 6.

Referring to the drawing, it will be seen that 45 I employ a single flat piece of fabric 11 which may be substantially circular or polygonal, or cut to an irregular pattern depending upon the appearance intended to be imparted to the finished beret. Said piece of fabric may bear a 50 suitable design and be provided with a lining material. If desired, there may be provided a lining coextensive with the outer fabric, and the lining and fabric may be secured together around the periphery, as by a fabric bead 12. At substantially equally spaced points around the

fabric, the material is stitched on itself to provide very narrow tucks 13, which may be anywhere from three to four inches in length depending on the head sizes to be fitted. From the inner end of each of said tucks or gathers, the fabric may be provided with lines of stitching as at 14 and 15, respectively, extending to the periphery of the fabric, the portions bounded by the lines 13 and 15 and the included edge of the fabric, forming triangles which are substantially bisected by the line of stitching 14.

One function of the gathers or tucks 13 is to stiffen the material, while lines of stitches 14, 15, mark convenient fold lines when the material is folded so that tuck 13 coincides with stitch line 15. Obviously, stitches 14 and 15 also serve to add a little rigidity to the fabric. A further function of the tucks 13 is to enable the folded materials 16 to lie flat. Obviously, though, the tucks 13 and the lines of stitching 14, 15 may be omitted, if desired.

In the preferred form shown in Figs. 1-5 inclusive, buttons 17 are provided around the periphery of the blank closely adjacent the demarcation lines 15; and buttonholes 18 are provided on each side of the tucks 13 adjacent the periphery, and in such manner that when the fabric is folded along the tuck 13 the two buttonholes will register with each other so that when the folded portion is brought over to coincide substantially with the line 15, the buttons 17 may be passed through their respective registered buttonholes 18, as more clearly shown in Fig. 3.

Obviously, other fastening means may be substituted for the buttons and buttonholes. One instance of such modification is shown in Figs. 6 and 7, wherein snap fasteners are used in place of buttons. The female element of the fastener is shown attached to one portion of the blank as at 17a, and the male element is attached to the fold as at 18a. In this instance, it is merely necessary to provide a perforation or opening in the intermediate fold of the fabric, as shown at 18', to permit the male fastening element to extend through to reach the female element and retain the three plies of fabric in place when folded.

As stated above, it is not necessary to provide the lines of stitching 13, 14, or 15, since the portion having the two buttonholes may be

merely pinched together with the thumb and forefinger to produce a fold with the two buttonholes in registry, and then this fold brought over to engage the buttonholes over the button 17.

When the several portions of the fabric have been folded in the manner described and illustrated, and said folds secured in place by means of the buttons and buttonholes, the article will have the appearance illustrated in Figs. 2 and 5.

While I have described what I deem to be the more desirable embodiments of my invention, it is obvious that many of the details may be varied without in any way departing from the spirit and scope of the invention as defined in the appended claim.

What I claim as new and desire to secure by Letters Patent is:

An article adapted to be formed into a beret comprising a flat piece of fabric polygonal in outline and having more than four sides, said piece being stitched to provide narrow tucks extending inwardly from the angles of the polygon to facilitate the forming of substantially uniformly spaced radially directed triangularly-shaped folds, with all of said folds being disposed in the same circular direction around the piece, coincidable buttonholes disposed on opposite sides of each tuck and buttons disposed intermediate the tucks and adapted to be engaged by the buttonholes when the tuck portions are folded over in the provision of the folds, the edge of the fabric pieces and folds therein being thus disposed to constitute the head band of the beret.
